UNITED STATES PATENT OFFICE.

FRANCES RADER, OF PRESCOTT, WISCONSIN.

DESIGN FOR A LAMP-HEATER.

SPECIFICATION forming part of Design No. 28,736, dated October 23, 1894.

Application filed August 16, 1894. Serial No. 520,526. Term of patent 7 years

To all whom it may concern:

Be it known that I, FRANCES RADER, of Prescott, in the county of Pierce and State of Wisconsin, have invented and produced a new and original Design for Lamp-Heaters, of which the following is a specification.

Reference is to be had to the accompanying drawing, in which the figure represents in perspective, a heater embodying my new design.

The leading feature of my design consists in the shape of the body, the same presenting the form of a truncated cone and having

a flat, annular, laterally-projecting flange at the top. 15

Another feature is the triangular openings in the flange.

I claim—

The design for a lamp-heater, consisting of a truncated, conical body and a flat, horizontal, annular top flange which overhangs said body and is provided with openings as shown.

FRANCES RADER.
